DESIGN FOR AN ELECTRIC BROILER

Chauncey E. Waltman, Chicago, Ill., assignor to
Finders Manufacturing Company, Chicago,
Ill.

Application October 20, 1944, Serial No. 115,887

Term of patent 14 years

(Cl. D81—10)

To all whom it may concern:

Be it known that I, Chauncey E. Waltman, a citizen of the United States, residing at Chicago, in the county of Cook and State of Illinois, have invented a new, original, and ornamental Design for Electric Broilers, of which the following is a specification, reference being had to the accompanying drawing, forming part thereof.

Fig. 1 is a front elevational view of an electric broiler, showing my new design;

Fig. 2 is a top plan view thereof; and
Fig. 3 is a fragmentary elevational view of the rear central portion of the broiler.

I claim:

The ornamental design for an electric broiler, as shown.

CHAUNCEY E. WALTMAN.
